[57] CLAIM

The ornamental design for a hose quick connector housing, as shown and described.

DESCRIPTION

FIG. 1 is a top, front, and left side perspective view of a hose quick connector housing showing my new design;

FIG. 2 is an enlarged left side elevational view thereof, the right side being a mirror image thereof;

FIG. 3 is an enlarged front elevational view thereof;

FIG. 4 is an enlarged top plan view thereof, the bottom being identical in appearance; and,

FIG. 5 is an enlarged rear elevational view thereof. The broken-line disclosure of internal features is for illustrative purposes only and forms no part of the claimed design.
